UNITED STATES PATENT OFFICE

OTTO M. SUMMERS, OF DAYTON, OHIO, ASSIGNOR TO FRIGIDAIRE CORPORATION, OF DAYTON, OHIO, A CORPORATION OF DELAWARE

REFRIGERATING APPARATUS

Application filed December 31, 1929. Serial No. 417,705.

This invention relates to refrigerating apparatus and more particularly to the evaporator or low pressure side of refrigerating apparatus.

5 An object of this invention is to provide improved means for maintaining a minimum amount of liquid other than refrigerant on, the low pressure side of the refrigerating system.

10 Another object of the present invention is to provide for the flow of such liquid from the evaporator by gravity and to utilize the change in pressure, due to the change in temperature of the evaporator, for controlling the flow of such liquid from the evaporator.

In carrying out the above objects, it is a further object to provide means for and a method of returning such liquid only during the latter part of the operating cycles of the refrigerating system.

20 Further objects and advantages of the present invention will be apparent from the following description, reference being had 25 to the accompanying drawings, wherein a preferred form of the present invention is clearly shown.

In the drawings:

30 Fig. 1 is a vertical section through a portion of an evaporator having my invention embodied therein and having a refrigerating system shown diagrammatically adapted to be connected with the evaporator; and

35 Fig. 2 is a fragmentary sectional view taken on lines 2-2 of Fig. 1.

In Fig. 1 is disclosed diagrammatically a portion of a refrigerating system comprising a compressor 10 for compressing the refrigerant, preferably sulphur dioxide, and 40 for forwarding it to the condenser 11 where it is liquefied and collected in the receiver 12. The actuating means for the compressor preferably comprises a motor 13 connected by pulley and belt means 14 to the compressor.

45 A supply conduit 15 supplies liquid refrigerant to the evaporator through the inlet connection 25 and a return conduit 16 connected to a gaseous refrigerant outlet connection 24 returns the refrigerant vapor 50 from the evaporator to the compressor 10.

A pressure responsive switch means 17 is preferably connected in the return conduit 16 for controlling the motor 13 to provide alternating operating and idle periods of the compressor according to the pressure and consequently the temperature of the evaporator.

The preferred type of evaporator as disclosed in the drawings comprises a boiler or tank 20, preferably of a cylindrical form, 60 having its end closed by a valve plate 21 secured in a supporting ring 22 by the screws 23 surrounding the opening in the boiler 20. The valve plate 21 has the gaseous refrigerant valve 24 and the liquid refrigerant 65 inlet valve 25 supported thereon. The inlet valve 25 for the liquid refrigerant enters into a gradually restricted passage through a boss 26 on the inner side of the valve plate. A supporting bracket 27 is attached to this 70 boss and supports a float ball 28 and float ball arm 29 operating the needle valve 30 for controlling the flow of liquid refrigerant into the evaporator.

The outlet valve 24 preferably communicates through the valve plate to an outlet tube 31 having an open end 32. Attached to this open end 32 is a casing 33 having an open upper end 34. In this open upper end is a screw threaded nut 35 having an open 80 portion 36. The bottom of the casing 33 is provided with an opening and has a valve 37 seated in this opening. A spring 38 preferably bears against the top of the valve and the under side of the nut 35 and tends to 85 keep the valve seated. The pressure of the spring can be adjusted by the nut 35. The valve 37 is connected to and controlled by a bellows 39 which is supported on any convenient structure such as the bracket 27a. The 90 bellows 39 is responsive to conditions within the evaporator, namely, it will expand when the temperature and therefore the pressure within the evaporator is lessened and contract when the temperature and therefore the 95 pressure within the evaporator is increased. Its complete collapse, however, is prevented by the resilient block 40.

In operation, the pressure responsive switch is set to maintain the pressure and consequent 100

ly the temperature within the evaporator between predetermined limits. When the pressure within the evaporator rises to the high limit corresponding to the high temperature limit required, the motor is started and the compressor withdraws refrigerant gas from the evaporator through the opening 36, tube 31, outlet connection 24 and suction line 16. The gas is compressed in the compressor and forced into the condenser 11 where it is condensed and collected in the receiver 12.

From the receiver the liquid refrigerant flows to the evaporator within which a constant quantity thereof is maintained by the float 28 operating the inlet valve 30.

15 The bellows 39 controlling the valve 37 is set to open at a pressure slightly greater than the pressure required to stop the compressor, and to remain closed above this point.

20 During the operation of the compressor, lubricant is circulated through the system with the refrigerant and means for returning the lubricant from the evaporator must be provided, otherwise the evaporator will become

25 less efficient. This lubricant collects in a layer on the top of the liquid refrigerant and consequently when the valve 37 opens just before the compressor stops, the lubricant above the valve opening 37 flows back 30 to the compressor crankcase. It will be understood, that the opening in the casing 33 is positioned slightly above the normal liquid refrigerant level so that no liquid refrigerant will be returned to the compressor.

35 Further by opening the valve 37 only just before the stopping of the compressor, the liquid refrigerant will not be boiling violently and consequently the lubricant may be removed easily and without carrying any liquid refrigerant mixed therewith.

40 While the device has been shown as removing lubricant from the top surface of the liquid refrigerant it is equally applicable for removing lubricant heavier than refriger- 45 ant by merely providing an extension conduit leading from the opening 37 to a point near the bottom of the evaporator.

45 It will be noted that the open upper end 50 of the casing 33 is adjacent the top of the tank 20 and therefore lubricant will not readily flow from the evaporator at this point. This is advantageous in that, if lubricant were permitted to escape while the boiling is violent, a certain amount of liquid refrigerant would be carried with the lubricant causing refrigeration outside the evaporator.

55 It is thus apparent that by the present invention I have provided for the return of lubricant when an excessive amount collects in the evaporator and I have arranged for the return of lubricant to the compressor when the boiling in the evaporator is less violent.

60 Preferably part of the air is withdrawn

from bellows 39, but it is to be understood that various pressures may be maintained therein and fluids other than air, and springs can be used to suit the requirements of different operating conditions of the evapora- 70 tor.

75 While the form of embodiment of the invention as herein disclosed, constitutes a preferred form, it is to be understood that other forms might be adopted, all coming within the scope of the claims which follows.

What is claimed is as follows:

1. A refrigerating system including an evaporator and a refrigerant supply unit for supplying liquid refrigerant to said evaporator, a lubricant adapted to accompany said refrigerant to said evaporator, means for operating said refrigerant supply unit in cycles, means to withdraw excess lubricant from said evaporator during the latter part only 80 of the operating cycle of the refrigerant supply unit comprising an outlet conduit having an opening in its upper portion for the passage therethrough of evaporated refrigerant and an opening in its under portion for said oil, and a valve opening and closing said last mentioned opening.

2. A refrigerating system including an evaporator and a refrigerant supply unit for supplying liquid refrigerant to said evaporator, a lubricant adapted to accompany said refrigerant to said evaporator, means for operating said refrigerant supply unit in cycles, means to withdraw excess lubricant from said evaporator during the latter part only 95 of the operating cycle of the refrigerant supply unit comprising an outlet conduit having an opening in its upper portion for the passage therethrough of evaporated refrigerant and an opening in its under portion for 100 said oil, a valve opening and closing said last mentioned opening, and pressure responsive means in said evaporator controlling said valve.

3. In refrigerating apparatus utilizing as 110 a working fluid a refrigerant and a lubricant which separate by gravity, means for maintaining a substantially constant quantity of liquid refrigerant in the evaporator, means for removing by gravity the lubricant collecting on the surface of the liquid refrigerant in the evaporator, said means including a valve disposed at the lubricant level desired to be maintained in the evaporator, and means responsive to conditions within said 115 evaporator for operating said valve.

4. In refrigerating apparatus utilizing as 120 a working fluid a lubricant and a refrigerant which separate in the evaporator by gravity, an evaporator means for supplying refrigerant and lubricant to said evaporator, and means having a portion disposed at the lubricant level desired to be maintained in the evaporator and responsive to conditions within 125 the evaporator causing the return by gray- 130

ity of separated lubricant to the first named means.

5. In refrigerating apparatus utilizing as a working fluid a lubricant and a refrigerant which separate by gravity in the evaporator, an evaporator, means for supplying lubricant and refrigerant to said evaporator, means causing the return by gravity of the lubricant from the evaporator to said first named means, said means including a valve disposed at the lubricant level desired to be maintained in the evaporator, and means responsive to the pressure within the evaporator for operating said valve.
- 10 6. In refrigerating apparatus utilizing as a working fluid a mixture of refrigerant and lubricant capable of separating by gravity, an evaporator, a compressor and a condenser connected in a closed cycle, a motor for driving said compressor, means responsive to the pressure within said evaporator for starting and stopping said motor at predetermined high and low pressures within said evaporator, means for returning lubricant by gravity 20 from the evaporator to said compressor including valve means, means responsive to the pressure within the evaporator for opening and closing said valve, said last named means being effective to open said valve at a pressure slightly in excess of that required to 25 stop said motor.
- 30

In testimony whereof I hereunto affix my signature.

OTTO M. SUMMERS.
